UNITED STATES PATENT OFFICE

163,644

MINE CAR WHEEL

Ray O. Shive, Belleville, Ill., assignor to Sterling Steel Casting Company, Monsanto, Ill., a corporation of Illinois

Application August 22, 1949, Serial No. 4,647

Term of patent 14 years

(Cl. D14—30)

To all whom it may concern:

Be it known that the undersigned, Ray O. Shive, a citizen of the United States, residing at Belleville, Illinois, has invented a new, original, and ornamental Design for Mine Car Wheel, of which the following is a specification, reference being had to the accompanying drawing, forming a part thereof, in which:

Fig. 1 is an end elevational view of a mine car wheel, showing my new design;

Fig. 2 is a front elevational view thereof;

Fig. 3 is a rear elevational view thereof; and

Fig. 4 is a radial sectional view of the rim at a point midway between the spokes.

The characteristic feature of the invention resides in the arcuate legs of substantially round cross section.

I claim:

The ornamental design for a mine car wheel, substantially as shown and described.

RAY O. SHIVE.
